CLAIM

The ornamental design for pivot collar of adhesive tape, as shown and described.

DESCRIPTION

FIG. 1 is a perspective view of pivot collar of adhesive tape showing my new design thereof;

FIG. 2 is a front elevational view thereof;

FIG. 3 is a rear elevational view thereof;

FIG. 4 is a left side view and the right side elevational view being a mirror image thereof;

FIG. 5 is a top plan view thereof and the bottom plan elevational view being a mirror image thereof; and,

FIG. 6 is another side perspective view of pivot collar of adhesive tape showing our new design thereof.
